UNITED STATES PATENT OFFICE.

CHARLES S. PROUDFOOT, OF WESTMONT, AND DAVID L. EYNON, OF BETHLEHEM.
PENNSYLVANIA.

FRAME FOR SIDES OF CAR TRUCKS.

Application filed February 24, 1923. Serial No. 620,894.

To all whom it may concern:

Be it known that we, CHARLES S. PROUDFOOT, a resident of the borough of Westmont, county of Cambria, and State of Pennsylvania, and DAVID L. EYNON, a resident of Bethlehem, county of Northampton, and State of Pennsylvania, both citizens of the United States, have invented certain new and useful Improvements in Frames for Sides of Car Trucks; and we do hereby declare the following to be a full, clear, and exact description of the invention, such as will enable others skilled in the art to which it appertains to make and use the same.

Our invention relates generally to a frame for the side of a car truck, which may be used with any kind of cars, but which is especially adapted for use under freight cars of large capacity.

Our frame has all of its principal members formed of one plate of metal, preferably of steel, which is first cut, sheared or punched to the outlines desired, and flanges are then formed on its various edges in any manner, but preferably by a flanging press with suitable dies, and in doing this the plate may be cold, but we prefer the flanging shall be done when the plate is hot.

The plate is cut in such a way as to ultimately form the principal members of what is known as an integral arch bar type of truck side frame, comprising the top arch bar, with deeper end extensions, into which are merged the end portions of the diagonal tension members; upright portions forming the column guides and bounding the bolster opening, a bottom arch bar; inclined tension members connecting the bottom arch bar with the end extensions of the top arch bar, and we also prefer to form the pedestal tie bars integral with the other members.

Certain of the flanges project inwardly and in some cases have marginal flanges which project outwardly therefrom, and when the parts are in their finally formed position the outstanding flanges are preferably secured together by spot welding.

The plate after being cut to shape and flanged is bent about its median line with certain of the inturned flanges opposite each other, while the outstanding flanges which are provided on some portions are parallel to each other and are adapted to have their sides in close contact in such a way that they may be readily grasped between the jaws

or electrodes of a spot welding apparatus and be secured by welding together at intervals thereby. Separate plates or pads may be welded to the upper boundaries of the bolster opening to serve as column guides, and the usual journal box bolt holes are also provided in the ends of the top arch bar and in the pedestal tie bars, and we may also add a bent reinforcing plate within each extension end of the top arch bar to reinforce it and serve as nut locks for the column bolts.

The structure when completed has its principal members of hollow box form, which may be entirely closed or with spaces between certain of the flanges, and the side portions are spaced apart a predetermined distance so that the entire structure is stiff and strong and the material arranged therein to good advantage to withstand the stresses of use.

In order to lighten the weight of the frame and to permit access to the truck brake shoes, etc., we provide openings between the bolster opening and the ends of the frame, which in this case are shown as circular, but they may be of any other shape desired, and are provided with inturned flanges which are opposite each other in order to strengthen the structure and provide a neat finish therefor.

Having thus given a general description of our invention, we will now, in order to make the matter more clear, refer to the annexed sheet of drawings, which forms part of this specification, and in which like characters refer to like parts:—

Figure 1 is a side elevation of our frame for the side of a car truck, showing the wheels journals, journal box bolts and end reinforcing plates in dotted lines; Figure 2 is a bottom plan view of our frame looking upwardly; Figure 3 is a vertical cross sectional elevation taken on the line III—III of Figure 2; Figure 4 is an end elevation of the frame; Figure 5 is a vertical cross section through the end portion of the frame on the line V—V of Figure 1; Figure 6 is a cross section of the intermediate portion of the pedestal tie bar taken on the line VI—VI of Figure 1; Figure 7 is a cross section of the inclined tension member taken on the line VII—VII of Figure 1; Figure 8 is a cross section taken at the central portion of the end of the pedestal tie

bar between the journal box bolts on the line VIII—VIII of Figure 1; Figure 9 is a cross section near the end of the pedestal tie bar on the center line of the outer journal box bolt hole taken on the line IX—IX of Figure 1, and Figure 10 is a cross section through the lower portion of the column guides taken on the line X—X of Figure 1.

Referring now to the characters of reference on the drawings:—1 is the top flange or that portion of the top arch bar which is formed from the central portion of the plate and is of substantial width as shown, corresponding to the general width of the frame; 2 are the side portions formed integral therewith and extending downwardly therefrom in substantial parallelism; 3 are the openings between the column guides and the ends of the frame, which are shown as circular and are bounded by the inturned flanges 4, which are opposite and spaced apart; 5 are the inturned flanges of the central portion of the top arch bar, which are opposite each other and spaced apart; 6 is the bolster opening, which is wider at the bottom than at the top in order to receive the springs and allow the bolster to be placed and replaced as necessary; 7 are the inturned flanges at the lower parts of the side of the bolster opening, which as shown, are opposite and slightly spaced apart; 8 are plates, originally separate, which are integrally secured to the upper portions of the column guides by welding or otherwise, and which serve as guides for the movement of the bolster; 9 are the inturned upper flanges of the central portion of the lower arch bar, the edges of which are spaced apart as illustrated; 10 are the lower flanges of the end extensions which are adapted to rest upon the journal boxes and preferably abut each other to make close contact, and if desired may be welded together, and have journal box bolt holes therein; 11 are the out-turned flanges of the inclined tension member, the sides of which are contiguous and are secured together by the spot welds 12, as illustrated; 13 are similarly out-turned flanges of the bottom arch bar member, which when the parts are assembled project downwardly in substantial parallelism in close contact and are secured together by means of the spot welds 14, as illustrated; 15 are the upper end portions of the pedestal tie bars which form integral extensions of the inner and flanged portions thereof and overlie and are in close contact with the lower end portions 16 of the pedestal tie bars. The intermediate portions of each of these extensions is flanged at substantially right angles with the other portion, and these flanges 17 extend downwardly, are contiguous and secured together by spot welds 18. These pedestal tie bar extension portions are provided with holes 19 to receive the ends of the

journal box bolts. 20 are channel shaped reinforcing plates with the webs thereof cut to trapezoidal form and with upturned end portions to serve as nut locks for the journal box bolts, and these reinforcing plates 70 are inserted within the ends of the upper portion of the frame and secured thereto by welds 21, which may be edge welds formed by depositing similar fused material against portions of their edges and also fused to the 75 adjacent edges of the plates of the frame. Some of the welds are shown as circular, and these are formed by providing holes in the sides of the end portions of the frame, which are then filled with material which is fused 80 therein and welded to the reinforcing plate 20 and also to the plate forming the boundary of the hole, thus somewhat resembling the shank of a rivet, but fused to both portions to hold the reinforcing plates very 85 firmly in position. Journal box bolt holes 22 are provided in the lower flanges 10 of the end extensions of the frame, and 23 is the spring plank shown in dotted lines in Figure 10, which may be secured to the frame 90 in any manner desired, and which extends from one side of the truck to the other to hold the two frames together in alignment and also supports the springs.

Our frame is preferably made in the following manner:—A plate of metal, preferably of steel, about one-half inch or thereabouts in thickness and substantially rectangular, is placed on a powerful shearing press and cut to shape thereon in one or two operations as desired. After this is done the plate is preferably heated and placed in a powerful flanging press and the various flanges are pressed integrally therefrom and some of them extend substantially at right 100 angles to the body of the plate and are joined thereto by rounded corners with substantial radii, while the flanges which project downwardly in the finished frame, such as 11, 13 and 17, are formed substantially 105 parallel to the side portions of the body of the frame. The plate is then placed in another press and bent about its median line and the two sides bent toward each other so that the like parts are substantially opposite each other, and the side portions are then closed together. The frame is then firmly clamped to hold the flanges 11, 13 and 17 in close contact and the spot welds 12, 14 and 18 are made, which secure the different parts 110 together.

The reinforcing plates 20 are then inserted and welded in place. The journal box bolt holes may be previously formed or made after the frame is shaped. The column guide plates 8 are also placed in position and welded or secured to the upper portions of the column guides as illustrated.

It will thus be seen that by means of our construction we provide a very simple and 130

effective way for securing the different parts together by their outwardly extending flanges and the spot welding of the same, these flanges being readily accessible for this purpose, and the structure when complete forms a very substantial frame, which is easily made, and the different portions of which are secured together firmly and in a simple and effective manner.

10 Although we have shown and described our invention in considerable detail, we do not wish to be limited to the exact and specific details thereof as shown and described, but may use such modifications in, substitutions for, or equivalents thereof as are embraced within the scope of our invention, or as pointed out in the claims.

Having thus described our invention, what we claim and desire to secure by Letters 20 Patent is:—

25 1. A truck frame composed of one metal plate, having a top portion, two side portions extending therefrom and spaced apart, some parts of said side portions having inwardly extending flanges and other outwardly extending flanges integral therewith, secured together by welding.

30 2. A truck frame composed of one metal plate, having a top portion, side portions extending therefrom and spaced apart, some parts of said side portions having inwardly extending flanges and other outwardly extending flanges integral therewith, secured together by spot welding their contiguous 35 surfaces.

35 3. A truck frame composed of one metal plate, including a top portion, a bottom portion, and side portions composed of members connecting the same, said side portions being spaced apart and provided with in- 40 turned flanges substantially opposite each other, other flanges formed integral with some of the inturned flanges, projecting outwardly therefrom, in contact, and secured 45 together by welding.

45 4. An integral frame for car trucks, composed of a single plate of metal forming the various members thereof, having side portions extending from the upper portion

in substantial parallelism and spaced apart, integral inwardly extending flanges and outwardly extending flanges projecting therefrom with their sides in contact, and secured together by spot welding.

5. A frame for car trucks of the integral 55 arch bar type, comprising a single plate of metal bent about its intermediate portion, forming two sides spaced apart and opposite each other, openings formed therein, integral inturned flanges on said sides, certain 60 of the portions of which are provided with outwardly extending flanges formed integral with said inturned flanges, in contact with each other and secured together by spot welding.

6. A frame for a car truck, composed of a single plate of metal bent about its intermediate portion, forming side portions extending from the top portion, spaced apart and provided with integral inturned flanges, 70 pedestal tie bars formed integral therewith, the ends of which are overlapping and provided with centrally arranged integral flanges extending therefrom, and secured together by spot welding.

7. A frame for the side of a car truck, composed of a single plate, cut in the shape desired to form the various members, including the top arch bar member, the bottom arch bar member, inclined tension members, column guides, and pedestal tie bars, the side portions of which extend from the upper portion, are spaced apart and provided with inturned flanges, some of which are abutting and secured together, others 85 being opposite and spaced apart, and others provided with outwardly extending flanges, the sides of which are contiguous and secured together by spot welding.

8. A frame for the side of a car truck, 90 composed of various members, portions of some of which are provided with outstanding contiguous flanges, secured together by spot welding.

In witness whereof we hereunto affix our 95 signatures.

CHARLES S. PROUDFOOT.
DAVID L. EYNON.
